UNITED STATES PATENT OFFICE.

JAMES CHARLES ROYCE, OF TORONTO, ONTARIO, CANADA.

ELECTRICAL CONNECTOR.

1,021,377.

Specification of Letters Patent. Patented Mar. 26, 1912.

Application filed May 20, 1910. Serial No. 562,412.

To all whom it may concern:

Be it known that I, JAMES CHARLES ROYCE, a subject of the King of Great Britain, and resident of the city of Toronto, 5 county of York, Province of Ontario, in the Dominion of Canada, have invented certain new and useful Improvements in Electrical Connectors; and I do hereby declare that the following is a full, clear, and exact description of the same.

The invention relates to improvements in electrical connectors, as described in the following specification and illustrated in the accompanying drawings that form part 15 of the same.

The invention consists essentially in the novel construction and arrangement of parts, whereby a split pin expansibly secured in an insulated block is adapted to 20 make electrical contact with a tubular contact member, and whereby the wire leading to the removable portion of the connector is held by a block clamped thereon.

The objects of the invention are, to obtain 25 a perfect electrical contact in a separable connector, to allow the adjustment of the contact members in case of wear, to obviate the breaking of the wires leading to the removable portion of the connector, and 30 to devise a simple and cheap form of connector in which the separable portion will hold securely.

In the drawings, Figure 1 is a perspective view of the connector showing the two members separated and the upper block of each partly broken away. Fig. 2 is a plan view of the connector with the upper or covering blocks removed and showing the members joined together. Fig. 3 is a vertical longitudinal sectional view through the center of 40 one of the electrical contacts.

Like numerals of reference indicate corresponding parts in each figure.

Referring to the drawings, 1 is a block of 45 insulating material formed with a pair of recesses 2 in the upper face thereof and a bolt hole 3 extending through the center.

The recesses 2 are formed to receive the round headed split pins 4 and are preferably just one-half the depth of said pins. The semi-cylindrical portions of the said recesses are slightly larger than the stem portions of the said pins.

5 are counter-sunk head screws extending through the head portions of the split pins 4, said heads being counter-sunk on the

upper side to allow the heads of the screws to fit snugly thereinto and flush on the top. The screws 5 extend through the block 1 and the support 6 upon which the block 60 rests and are connected to electrical connector strips 7 secured on the opposite side of the support 6.

8 is a block similarly formed to the block 1 and fitting over the top thereof and resting snugly down upon the top of the pins 4, said block being secured in place by the screw 9. The stem ends of the pins 4 project outwardly beyond the blocks in which they are secured and the outer ends thereof 70 are rounded off.

10 is a block of insulating material having a pair of semi-cylindrical shaped recesses 11 formed in the upper face thereof, said recesses being slightly reduced at the 75 forward end 12 and terminating at the rear end in flat portions 13.

14 is a recess formed at the other end of the block 10 and communicating with both of the flattened recesses 13.

15 is a semi-cylindrical recess centrally arranged and leading outwardly from the recess 14 to the outer end of the block 10.

16 is a bolt hole extending through the block 10 and centrally arranged in the recess 14.

17 are tubular contact members resting snugly in the semi-cylindrical recesses 11 having their forward ends abutting the shoulders formed by the reduced portions 90 12 of said recesses. The opposite ends of the contacts 17 are flattened out and rest upon the flat surfaces of the recesses 13.

18 are bolts extending through suitable bolt holes in the flattened ends of the contacts 17 and having their heads countersunk into suitable recesses in the bottom of the recesses 13, said bolts forming binding screws.

19 is a block adapted to fit into the recess 14 and having its outer edges cut away to the underside forming grooves adapted to receive the wires 20 leading inwardly through the recess 15. The terminal ends of the wires 20 are secured to the bolts 18 by suitable nuts and the block 19 is clamped down tightly upon the said wires by a nut 21 threaded on the bolt 22 extending upwardly through the bolt hole 16.

23 is a block of similar formation to the block 10 adapted to fit over the tubular contacts 17 and to completely close in the top

of said block 10. The cover block 23 is clamped down securely to the block 10 by the nut 24 threaded on to the bolt 22 and by the bolt 25 extending through both of said blocks and arranged between the contacts 17.

26 is a spring coil encircling the wires leading to the removable portion of the connector and secured at the inner end in the recess 14.

10 The tubular contact members are held very securely in place and cannot become dislodged and being unbroken in their cylindrical shape they cannot be unduly expanded so as to be too loose for the proper 15 reception and contact of the pins 4. Further the said contacts 17 are completely insulated the one from the other and a short circuit cannot accidentally be made between their terminal ends. The split pins 4 which 20 are adapted to fit snugly into the tubular contacts 17 engage the side walls of said contacts and make a perfect electrical contact therewith. The pin members are formed up of semi-circular shaped wire and 25 the flat meeting faces are always held slightly apart and the two portions have an outward springing tension.

In the event of the pins 4 becoming slightly worn and the members becoming 30 a little loose, it is merely necessary to remove the cover block 8 and tighten the screws 5 slightly. The counter-sunk heads of the screws 5 press into the counter-sunk 35 heads of the pins and spread the two members forming the stem of the pins apart. Any desired spring outward tension may be thus given to the said pins so that when the removable portion of the connector is forced on to the ends of said pins, it will be held 40 very securely in place and will not come apart very readily. The clamping block 19 is a very important feature, as it grips the wires leading to the tubular contacts very securely and for a considerable length, 45 thus relieving the strain upon the terminal ends of the wire, where they are connected to the tubular contact members.

This form of connector is particularly adapted for use in electric stoves, heaters, 50 irons and other such like utensils. Split pins are well known and as the tubular portions are very easily made out of lengths of tubing, the cost of manufacture is exceptionally low.

55 What I claim as my invention is:

1. In an electrical connector, the com-

bination with a suitable socket member, of a block of insulating material, an expandable longitudinally split pin secured to said block, and adjustable means for expanding 60 said pin secured in said block and extending transversely through the split of said pin.

2. In an electrical connector, the combination with a suitable socket member, of a block of insulating material, a split pin 65 secured in said block and having a transverse orifice therethrough, and a tapered spreader adjustably secured in said block and extending through the orifice in said pin. 70

3. In an electrical connector, the combination with a suitable socket member, of a block of insulating material, a split pin formed of semi-cylindrical shaped wire doubled and formed with a looped head, a 75 counter-sunk headed screw extending through the looped head of said pin and into said block, and a threaded member secured to said block and adapted to receive the threaded end of said screw. 80

4. In an electrical connector, the combination with a suitable socket member, of a block of insulating material having a recess formed in the face thereof opening to one edge, an expandable longitudinally split 85 pin having its head resting in said recess and the stem extending beyond one edge of said block, adjustable means for expanding said pin secured in said block and extending through the split of said pin, an insulating 90 block adapted to fit over the aforesaid block to completely cover in the head portion of said pin resting in the aforesaid block, and means for clamping said blocks together. 95

5. In an electrical connector, the combination with a suitable socket member, of a block of insulating material, an expandable longitudinally split pin resting in said block, an electrical conductor connected to said block, and an adjustable expanding member 100 extending transversely through the split of said pin and forming an electrical connection between said pin and said electrical conductor.

Signed at the city of Toronto, county of 105 York, Province of Ontario, in the Dominion of Canada, this 18th day of May, 1910.

JAMES CHARLES ROYCE.
